UNITED STATES PATENT OFFICE.

ALMA MONFILS, OF CHICAGO, ILLINOIS.

DESIGN FOR A COMB HOLDER.

Application filed May 26, 1924. Serial No. 9,705. Term of patent 7 years.

To all whom it may concern:

Be it known that I, ALMA MONFILS, a citizen of the United States, residing at Chicago, in the county of Cook and State of Illinois, have invented a new, original, and ornamental Design for Comb Holder, of which the following is a specification, reference being had to the accompanying drawing, forming part thereof.

In the drawing, Fig. 1 is a plan view of my design for Comb-Holder; Fig. 2 is a front elevation of Fig. 1; and Fig. 3 is an end view of Fig. 2, showing a comb in the holder, by dotted lines.

I claim:

The ornamental design for a comb holder, as shown.

Chicago, Ill., April 28, 1924.

ALMA MONFILS.
